UNITED STATES PATENT OFFICE

HERMAN BAUER, OF STUTTGART, GERMANY

MACHINE FOR SORTING FEATHERS

Application filed March 18, 1929, Serial No. 348,018, and in Germany March 20, 1928.

My invention relates to machines for treating bed feathers and more particularly to sorting machines, and is an object of my invention to provide a machine of this type which operates continuously.

To this end I provide a suction passage extending throughout the machine, and sorting chambers arranged along the passage and adapted to be connected with the passage.

10 In machines as designed heretofore the sorting chambers were arranged in series. Such machines cannot be operated continuously but require periodical charging of the machine, the machine being inactive during 15 the charging periods.

In my machine, on the other hand, the suction passage aforesaid constitutes a conveyer at one end of which the feathers are charged continuously while at its other end the residue, consisting principally of too coarse feathers, is discharged continuously.

20 One or more sack chambers may be allotted to each sorting chamber. The sack chambers are operated periodically to draw the sorted feathers from the sorting chambers into their respective sacks and it is another object of my invention to prevent interference with the continuous operation of the machine by the 25 intermittent operation of the sack chambers.

30 To this end I combine with each unit comprising a sorting and a sack chamber, an intermediate or transit chamber which is alternately connected with the sorting chamber and the sack chamber. When connected with 35 the sorting chamber it receives the sorted feathers from the chamber and when connected with the sack chamber it permits removal of the sorted feathers into the sack chamber while the sorting operation goes on 40 in the sorting chamber.

In the accompanying drawings a machine embodying my invention is illustrated diagrammatically by way of example.

45 In the drawings

Fig. 1 is an elevation of the machine, with its suction passage or conveyer partly broken open,

50 Fig. 2 is a plan view, with one of the transit chambers partly broken open,

Fig. 3 is a section on the line 3—3 in Fig. 1, and

Fig. 4 is an end elevation of the machine viewed from the left in Fig. 1.

Referring now to the drawings, 1 is the suction passage or conveyer which as shown is made of tubes of increasing diameter toward the rear but may be tapered or of uniform diameter throughout, 2 is a charging hopper at the front end of the conveyer, 3 is a rotary stirrer in the conveyer, 4 is the rear end of the conveyer, 5 is a fan near the rear end 4, and 6 are the sack chambers, in the present instance four.

7, 8, and 9 are uptakes arranged along the conveyer 1 and connected therewith at its upper part, 107, 108, and 109 are sorting chambers connected with the respective uptakes, 10 is another fan, 12, 12 is a suction pipe extending from the fan to the several sorting chambers 107, 108, 109, and 13, 13 are branch pipes connecting the suction pipe 12 with the chambers. 18 is a transit chamber for each set of a sorting and a sack chamber, and 19 is a stirrer in the transit chamber.

The feathers are gradually sorted while moving along the conveyer 1, the lightest constituents, the down, being separated first. They are subjected to a combined suction action, one at right angles to, and the other axially along, the conveyer 1 while being agitated by the stirrer 3.

29 are dampers in the branch pipes 13 of the suction pipe 12, 14 is mechanism for operating the dampers, and 15 are handles for operating the mechanism.

Each of the sorting chambers, as shown for the chamber 107 in Fig. 3, is provided with a bottom flap 16 connecting it with the transit chamber 18 below when in the dotted-lines position, and 17 is a shaft for operating the flap. The fan 5 draws the finished feathers from the transit chambers and delivers them to the allotted sack chamber or chambers 6, 20 being the sacks in the chambers. To prevent interference with the sorting operation in the several chambers 107, 108, and 109 by the flow of air to the fan 5, when the respective flaps 16 are opened, means must be provided for interrupting the connection of the

fan with the transit chamber the flap of which is open. Such means as illustrated in Fig. 4 may comprise rocking levers 22, 22, a cam 24 operatively connected with the rocking levers at one end, a link 23 at the other end for controlling the flaps 16, and mechanism generally indicated by 25 for controlling a valve 26 which admits air from the outside to the transit chambers 18, and a valve 27 in the suction pipe 28 of each sack chamber 6. The control is such that when the flaps 16 are closed the corresponding valves 26, 27 are open, and vice versa.

In operation feathers are continuously charged into the hopper 2 and drawn into the passage or conveyer 1 by the suction therein. In this manner they move from one end of the conveyer to the other while being stirred by the stirrer 3 and are extracted by the suction in the uptakes 7, 8, and 9. The non-extracted feathers travel on axially in the conveyer 1. In this manner the machine is operated without intermission and the time which the feathers take for moving past the several uptakes may be so determined as to reliably select the desired categories of feathers.

I claim:

- 30 1. A machine for treating bed feathers comprising a tubular conveyer extending along said machine, means for charging feathers into said conveyer, means for reducing the pressure in said conveyer, sorting chambers arranged along, and connected with, said conveyer, means for reducing the pressure in said sorting chambers, a transit chamber allotted to each sorting chamber, and means for temporarily connecting said transit and sorting chambers.
- 35 2. A machine for treating bed feathers comprising a tubular conveyer extending along said machine, means for charging feathers into said conveyer, means for reducing the pressure in said conveyer, sorting chambers arranged along, and connected with, said conveyer, means for reducing the pressure in said sorting chambers, a transit chamber allotted to each sorting chamber, means for temporarily connecting said transit and sorting chambers, means for reducing the pressure in said transit chamber, and means for disconnecting said reducing means from said transit chamber while said chambers are connected.
- 40 3. A machine for treating bed feathers comprising a tubular conveyer extending along said machine, means for charging feathers into said conveyer, sorting chambers arranged along, and connected with, said conveyer, means for reducing the pressure in said sorting chambers, a sack chamber allotted to each sorting chamber, means for reducing the pressure in said conveyer and said sack chambers, a transit chamber intermediate each sorting and sack chamber, and

means for alternately connecting said transit chamber with said sorting chamber and said pressure-reducing means.

In testimony whereof I affix my signature.

HERMAN BAUER.
